UNITED STATES PATENT OFFICE.

WILLIAM M. HOLLADAY, OF HOULKA, MISSISSIPPI.

PLANTER.

SPECIFICATION forming part of Letters Patent No. 486,971, dated November 29, 1892.

Application filed June 21, 1892. Serial No. 437,467. (No model.)

To all whom it may concern:

Be it known that I, WILLIAM M. HOLLADAY, a citizen of the United States, residing at Houlka, in the county of Chickasaw and State of Mississippi, have invented a new and useful Planter, of which the following is a specification.

My invention relates to improvements in planters, the objects in view being to provide a cheap and simple construction of planter adapted for planting corn, cotton, peas, or sorghum at predetermined distances apart and so constructed as to open and close the furrows for receiving the seed.

Other objects and advantages of the invention will appear in the following description, and the novel features thereof will be particularly pointed out in the claim.

Referring to the drawings, Figure 1 is a perspective view of a planter constructed in accordance with my invention. Fig. 2 is a vertical longitudinal sectional view of the same. Fig. 3 is a detail in vertical longitudinal section of the cotton-seed hopper. Fig. 4 is a transverse section of the machine. Fig. 5 is a plan view of the machine, the rear portion being broken away.

Like numerals indicate like parts in all the figures of the drawings.

1 designates the opposite side bars of the frame, whose front ends embrace and are pivotally bolted to a tongue or draft-bar 3 by means of a transverse bolt 2, which bolt also passes through the front lower ends of a pair of upwardly-disposed handles 4. These handles are connected near their rear ends by a transverse rung 5 and are supported by inclined standards 6, the lower ends of which are by a bolt 7 connected to the side bars 1 and the upper ends of which are bolted at 8 to the aforesaid handles.

Upon the same bolt 7 as the standards 6 are secured there is mounted a block 9, the same being adapted to loosely swing upon the bolt and interposed between the rear ends of the bars 1. This block has its rear end tenoned and held into a mortise formed in the center of a transversely-disposed harrow-bar 10, whose under side is curved or cut out and provided at opposite sides of its center with depending harrow or cultivator teeth 11.

Hinged at 12 to the block 10 is the lower

end of a rod 13, whose rear edge is provided with an upper half-opening 14 and a lower similar opening 15. Either of these openings 55 may be arranged so as to receive the rung 5, and when the upper opening receives the rung the harrow is lowered to an operative position, and, on the other hand, when the lower opening 15 engages the rung the harrow is raised 60 from an operative position. The bar may be secured in either of its positions through the medium of a turn-button 16, which is pivoted to the rear edge of the bar 13 between the openings 14 and 15.

In bearing-openings formed in the side bars 1 an axle 18 is located, and the same at its outer ends, beyond the bars, is provided with a pair of ground-wheels 19 and between its bearings with a circular boss 20, whose periphery is provided with an annular series of perforations 21, in any number of which radiating spokes 22 may be inserted. These spokes are removable and may be increased or decreased in number, so as to occupy only 75 a portion of the number of perforations or the entire number, and in accordance therewith the machine will be regulated to plant the seed a proper distance apart, all as in the manner hereinafter apparent. A platform 80 23 surmounts the frame of the machine and is provided at its center with an opening. This platform is surmounted by a hopper 24, whose bottom has a seed-discharge 25, and is recessed to receive a slide 26, whose front end 85 is bifurcated at 27, and which is provided between its ends with a seed-opening 28. The discharge-opening 23a in the platform 23 is in advance of the discharge-opening 25 of the hopper, and by a reciprocation of the seed-slide seed that have passed through the hopper into the seed-opening of the slide will be brought opposite and dropped through the discharge-opening of the platform. A coiled spring 29 has its ends connected at 30 to the 95 opposite sides of the hopper and between its ends is sprung over into and between the bifurcations 27 of the seed-slide. The seed-slide is provided upon its under side with a depending lug 32, and the same is arranged 100 in the path of the spokes or arms 22, projecting from the cylindrical boss 20 of the axle 18, so that as the machine is moved the ground-wheel imparting motion to the axles success-

ively brings the spokes or arms extending from the boss against the rear side of the depending lug of the seed-slide and forces the same forward against the tension of its spring 5 29, which latter as soon as the slide is released retracts and returns it to its former position, where it receives a further supply of seed, and, being again struck, is advanced to a point over the opening in the platform, so that it 10 discharges therein.

33 designates a standard which depends from between the bars 1 and is bolted at 34 to said bars. The standard carries at its lower end a furrow-opening shovel 35 and is 15 provided at its rear edge with a discharge-tube 36, the upper end of which is in communication with the opening in the platform, so that seed passing through the opening will be connected by the discharge-tube to a point 20 directly in rear of the furrow-opening shovel.

The operation of the machine will be readily understood from the foregoing description, and may be briefly stated as follows: As the 25 axle revolves and the seed-slide is reciprocated in the manner heretofore described the seed, whether corn, peas, or sorghum, will be caught by the opening in the slide and conducted from the hopper in predetermined quantities (in accordance with the size of the 30 opening in the slide) to the opening in the platform, and from thence by the seed-spout to a point in rear of the furrow-opening shovel. This shovel, as its name implies, opens the furrow for the reception of the seed, and 35 the harrow or cultivator teeth following thereafter at each side of the furrow serve to replace the loose earth thrown from the furrow, and thus effectually cover the seed. In this manner the furrow-opening, planting, and 40 covering are all accomplished in one continuous operation.

37 designates a hopper especially adapted for planting cotton, which hopper I have shown in detail in Fig. 3. The hopper 37 is to be 45 substituted for the hopper 24 when cotton-seed are to be planted. The hopper 37 has hinged to its rear upper edge at 38 a V-shaped

triangular flap 39, whose lower end extends down through the discharge-opening 40, formed by the converging side walls of the 50 hopper. The flap is provided with a longitudinally-disposed arm 41, and from the same depends a series of agitator-teeth 42. A spring 43 is secured to the rear face of the flap, and after projecting through an opening 44, formed 55 in the rear wall of the hopper, is connected to one of the standards 6 or any other suitable point. The operation of this cotton-seed hopper will be obvious from the foregoing description of the operation of the machine, the 60 only difference being that the seed-slide is omitted and the spokes or arms radiating from the axle come in contact with and operate to vibrate the hinged flap 39. During the operation of "laying by" the corn it will be seen 65 that I may accomplish not only this by my machine, but I may also plant peas simultaneously with such operation, thus economizing both time and labor in a manner that will be obvious.

Having described my invention, what I claim is—

In a machine of the class described, the combination, with a framework, an axle, ground-wheels mounted thereon, and a hopper located upon the framework and provided with a bottom having an opening, of a seed-slide mounted in the hopper, provided at its front end with a notch and provided with an opening, means for communicating a forward 75 motion to the slide, and a coiled-spring loop connected permanently at its ends to the sides of the opposite hopper and having its central or intermediate portion sprung over the front or notched end of the slide, substantially as 80 specified.

In testimony that I claim the foregoing as my own I have hereto affixed my signature in the presence of two witnesses.

WILLIAM M. HOLLADAY.
